UNITED STATES PATENT OFFICE.

ARTHUR HENROZ, OF BRUSSELS, BELGIUM.

COUNTERPATTERN USED IN THE MANUFACTURE OF TILES.

Application filed April 16, 1923. Serial No. 632,462.

To all whom it may concern:

Be it known that I, ARTHUR HENROZ, a citizen of the Kingdom of Belgium, and resident of Brussels, Belgium, have invented certain new and useful Improvements in Counterpatterns Used in the Manufacture of Tiles; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to counterpatterns used in the manufacture of tiles with encrusted designs made of sandstone, ceramic ware or other analogous materials. In this process of manufacture, the separation in the stencil-frame of the different coloured materials composing the design, is regulated by compartments which follow the lines of the design which it is desired to make.

In order to regulate the admission of each colour which should fill certain compartments and not others, there is applied each time on the stencil-frame a counterpattern, whose openings are arranged in such a manner as to coincide only with the particular compartments to be filled and which closes the other parts of the stencil.

Counter-patterns are known in which the openings for the passage of any one colour have approximately the same area as the corresponding compartments of the stencil which are thus left free and wide open. These counter-patterns have the serious disadvantage that at the points where the stencil openings are relatively large, the colour is irregularly distributed.

Other counter-patterns are likewise known, in which the bottom wall is provided with a series of openings of the same shape and size; such construction presenting the objection that the openings are filled uniformly regardless of the shape of the stencil. In the small parts of the latter, these openings are useless and only complicate the construction of the counter-pattern; and in certain cases, particularly when thick colours are used, or those which have a tendency to conglomerate, these openings become a hindrance in that they

needlessly impede the delivery of the material.

To overcome these defects, and to permit a ready and uniform distribution of the colour at the bottom of the mould, regardless of the complexity of the design, without obstructing any part of the colour passages, the counter-pattern according to my invention is provided with openings whose shapes and dimensions have three definite characteristics:

1. At the points where the area of the compartment is large, the circular openings have relatively large diameters to enable the colour to fall freely upon the bottom of the mould, these openings thus being designed to serve solely to guide and uniformly distribute the material;

2. At the points where the design presents relatively narrow parts, the openings formed in the counter-pattern correspond approximately to the partitions of the stencil, since in this instance there is no danger of the material being irregularly distributed;

3. At the points where the design has a complicated outline and where, for that reason, the uniform distribution of the colours is extremely difficult, the circular openings will have a smaller diameter, while still following the outline of the compartments, the area of the openings being just sufficient to permit the passage of the heavy material therethrough.

The drawing accompanying the present specification represents for the sake of example one constructional form of the invention.

Figure 1 is a view of the counter-pattern in plan, and

Figure 2 is a cross-section of Figure 1 on the line A—B.

Figure 3 is a plan view of a partitioned stencil corresponding to the counter-pattern shown, the compartments which should be filled with some one particular colour being shaded with dotted lines.

Figure 4 is a sectional perspective view, on line A—B, Figure 1, showing the different parts in assembled relation.

In these drawings the pattern or stencil is constituted by a frame 1 which is divided into different compartments 2 by thin vertical walls 3 which follow all the outlines of the design.

The counter-pattern 4 is placed in this stencil, the two being held in their relative positions by the mould (not shown), in which the tile is manufactured. The continuous edge 5 of the counter-pattern 4 rests on the upper face of the mould.

The holes 6 of suitable shape are formed through the counter-pattern in such a way as to allow the colour to pass across them 10 in order to be emptied into the corresponding partitions 2" of the pattern.

The openings provided in the counter-pattern have variable dimensions, so as to conform them to the size, shape and outline 15 of the stencil compartments. Hence, the passage of the colours is not hindered at any point and their distribution takes place uniformly in the different compartments. The counter-pattern according to 20 this construction has openings of greater diameter than is absolutely necessary to permit the passage of heavy material at the points where the compartments 2' (Figure 3) are located, so as to enable the colour 25 to fall to the bottom of the mould without encountering the difficulties or obstructions to its distribution, the openings serving merely to guide and uniformly distribute the material.

30 On the other hand, at the points where the contours of the design are complicated, and where, for that reason, the distribution of the colours is extremely difficult, the openings have a smaller diameter which 35 conforms approximately to that absolutely necessary to allow the heavy material to pass and to feed it in sufficient quantity to the different parts of the design.

In the case of compartments such as 40 those indicated at 2' which are of small size and where there is no danger of unequal distribution of the colouring material, the openings formed in the counter-pattern have exactly the same shape and size as the 45 compartments.

It goes without saying that the dimensions and shapes of the openings do not depend solely upon the form of the design, but equally upon the nature—heavy or thin— 50 of the colouring material.

Fig. 4 shows diagrammatically the elements specified above in working position.

In this figure, the counter-pattern 4 is placed on the work table 7 and masks the stencil 1, blocking the compartments of the latter which must not be filled, while leaving the colour entirely free to pass through the openings 6 in order to fall to the bottom of the corresponding compartments 2' and 2" of the stencil.

The improved counter-pattern can be used in any sort of process for the manufacture of ceramic tiles with encrusted designs, either by hand or by machine.

I claim as my invention:

1. In apparatus for the manufacture of ceramic tiles with encrusted designs in colour, the combination, with a stencil or pattern member having partitions forming compartments to receive material of different colours, of a counter-pattern whereon the colouring material is deposited embodying a plate formed with openings located directly above said compartments; said openings being of three different types comprising holes of relatively large diameter situated over compartments of comparatively large area, elongated apertures situated over comparatively narrow compartments and conforming exactly to the outline thereof, and relatively small holes supplemental to the first-named holes for filling in complicated areas of the design.

2. In apparatus for the manufacture of ceramic tiles with encrusted designs in colour, the combination, with a stencil or pattern member having partitions forming compartments to receive material of different colours, of a counter-pattern whereon the colouring material is deposited embodying a plate formed with openings located directly above said compartments; said openings comprising holes of relatively large diameter situated over compartments of comparatively large area, and relatively small holes supplemental to the first-named holes for filling in complicated areas of the design.

In testimony whereof I affix my signature in presence of two witnesses.

ARTHUR HENROZ.
